(57) **CLAIM**

The ornamental design for a portion of a motorcycle swing arm, as shown and described.

DESCRIPTION

FIG. 1 is a side elevational view of a portion of a motorcycle swing arm showing our new design;

FIG. 2 is a bottom perspective view thereof;

FIG. 3 is a front perspective view thereof;

FIG. 4 is a front elevational view thereof; and,

FIG. 5 is a top plan view thereof.

The broken line showing of the remainder of the swing arm is for illustrative purposes only and forms no part of the claimed design.
